Attorneys.

UNITED STATES PATENT OFFICE.

GEORGE KEITH AND WILFRED AMBROSE WHATMOUGH, OF LONDON, ENGLAND.

MEANS FOR CONTROLLING THE SUPPLY OF MIXTURE TO INTERNAL-COMBUSTION ENGINES.

Application filed May 13, 1922. Serial No. 560,851.

To all whom it may concern:

Be it known that we, GEORGE KEITH and WILFRED AMBROSE WHATMOUGH, subjects of the King of the United Kingdom of Great Britain and Ireland, and residing at London, England, have invented a certain new and useful Improvement in Means for Controlling the Supply of Mixture to Internal-Combustion Engines, of which the following is a specification.

This invention relates to means for controlling the supply of mixture to internal combustion engines, and comprises certain improvements on the apparatus described in the specification of Letters Patent No. 1317709 in which vaporized fuel is supplied to the throat of a Venturi tube through a valve governed by the difference in pressure between two points in the venturi.

The apparatus described in the said specification included provision for loading the piston of the governor as the governor valve shut off to allow for the circumstance that as the throttle valve is closed a higher vacuum is set up in the induction pipe, with the result that there is a tendency for air to enter at the valve stems and any other points of leakage.

In effect, provision was made to avoid such dilution of the mixture as to prevent firing.

It has been found in practice that there is a further reason for requiring to compensate the mixture, as it is possible to run an engine with a weak economical mixture which will fire satisfactorily under high compression, but will not fire when the engine is running light.

The use of a spring or similar device for loading the piston was not entirely satisfactory, as the adjustment of the spring was quite empirical.

We have now devised compensating means which effect a progressive increase of richness of the mixture as the vacuum in the induction pipe rises, the rate of increase being adjustable while the engine is running to meet exactly the necessities of the case, the progression being correct under all conditions of power and speed.

The invention comprises compensating means suitable for use where the admixture of fuel and air is effected between the throttle valve and the engine, and means suitable

for use where the throttle valve is arranged between the point of admixture of fuel and air and the engine.

The first case is illustrated diagrammatically in vertical section in Fig. 1; the second case is similarly illustrated in Fig. 2 of the accompanying drawings.

We shall first describe the arrangement shown in Fig. 1 in which the admixture of air with fuel that passes the obturator at C is effected between the throttle valve A and the engine, and which, like the apparatus described in the said specification, includes a piston D arranged to operate a hollow valve E. It will be understood that the valve E, through its graduated ports Z, controls the admission of fuel vapor from the pipe W to the induction pipe B and the engine. A port X is arranged to transmit the pressure which exists at the wider part of the Venturi tube B to the back of the piston D. At some point at the back of the piston D (say in the cover of the cylinder Y) there is a small opening leading from the outside air through a pipe I and controllable by a pet cock or the like at F. If this opening be closed entirely, the mixture in the induction pipe will remain constant throughout all conditions. If the cock at F be opened, the mixture in the induction pipe will become progressively richer as the throttle valve A is closed; or, rather, as the vacuum increases in the induction pipe. The greater the extent of opening of the pet cock at F, the greater will the increase of richness become as the vacuum in the induction pipe or Venturi tube B increases. As the throttle valve A is opened and the vacuum falls, the effect of the opening of the pet cock at F will diminish till it practically disappears altogether when the engine is running with the throttle valve full open.

This action is accounted for by reason that if the pet cock at F be entirely closed the static pressure at the back of the piston D will be the same as exists at the end of the port X in the Venturi tube B; but if the pet cock at F be slightly open there must be a flow of air along the port X from the back of the piston D into the Venturi tube B, the rate of such flow being greater the greater the vacuum in the induction pipe and therefore in the Venturi tube B. As such flow along the port X cannot take place without

a difference of pressure, it follows that the pressure existing at the back of the piston D must be greater than the pressure existing at the Venturi tube end of the port X, so that the higher the vacuum in the induction pipe the greater will be the difference between the pressure at the Venturi tube end of the port X and the pressure on the back of the piston D.

10. By variation of the opening of the pet cock at F exact compensation may be obtained throughout all conditions of pressure in the induction pipe. As the pressure existing in the induction pipe determines both 15 the amount of air leakage and also the final compression of the mixture, the compensating device ensures the correct degree of richness of the mixture.

In the second case (Fig. 2) where the 20 mixture of gas and air is effected in the Venturi tube H or choke bore at a point more remote from the engine than the throttle valve G, a small pipe M connects the gas or vapor side of the piston K and the engine 25 side of the throttle valve G, an adjusting valve at N being arranged at some point in the said pipe M. The piston K is connected with and operates a valve L controlling, through its graduated ports Z, the passage 30 of vapor fuel to the induction pipe H and the engine. When the adjusting valve at N is entirely closed, the mixture in the induction pipe will be constant throughout all conditions. If the adjusting valve at N be 35 opened, the mixture in the induction pipe will become progressively richer as the vacuum in the induction pipe beyond the throttle valve A increases.

The arrangement shown in Fig. 2 operates 40 by a direct addition of gas or vapor through the connecting pipe to the mixture which has been already provided by flow of gas or vapor past the obturator at J into the Venturi tube H in front of the throttle valve G. 45 As the throttle valve G is opened and the vacuum decreases in the induction pipe, the amount of enriching gas or vapor pulled

through the adjusting valve at N will correspondingly decrease.

Assuming that the adjusting valve at N 50 is set correctly for the highest vacuum, the decrease of enrichment will be at exactly the same relative rate as the decrease of air leakage at the valve stems, etc., due to the fall of 55 vacuum in the induction pipe.

What we claim is:—

1. For controlling the supply of mixture to internal combustion engines, the combination with the induction pipe leading to the engine, of a governor device comprising a valve in the path of the fuel component flowing to the induction pipe, a piston determining by its position the extent of opening of said valve, a cylinder in which said piston is movable, a valve controlling the admission of fuel to said induction pipe, a fluid conduit communicating with the chamber of said cylinder, and means for controlling the passage of fluid through said conduit; whereby a progressive increase in 70 the richness of the mixture as the vacuum in the induction pipe increases may be effected, the rate of increase being adjustable while the engine is running.

2. For controlling the supply of mixture 75 to internal combustion engines, the combination with the induction pipe, of a governor device comprising a valve in the path of the fuel component flowing to the induction pipe and a piston operatively connected 80 to said valve, a cylinder in which said piston is movable, a port connecting the induction system with the end of said cylinder remote from the engine, a pipe connected to said cylinder, and valve means fitted to said pipe 85

In testimony whereof we have signed our names to this specification in the presence of two subscribing witnesses.

GEORGE KEITH.

WILFRED AMBROSE WHATMOUGH.
